Term of patent 14 years

(Cl. D58—6)

FIG. 1.

FIG. 2.

FIG. 4. FIG. 5.

FIG. 6.

FIG. 5.

Figure 1 is a side elevational view of a combined bottle and cap showing my new design.

Figure 2 is a view similar to Figure 1 showing the bottle with its cap removed.

Figure 3 is an end elevational view taken from the left side of Figure 1.

Figure 4 is an end elevational view taken from the right side of Figure 1.

Figure 5 is a top plan view of Figure 1 on an enlarged scale; and

Figure 6 is a cross-sectional view on the same scale as Figure 5, taken on the line 6—6 of Figure 3.

The side not shown is the same as the side shown.
I claim:

The ornamental design for a combined flexible bottle and cap, as shown and described.
